UNITED STATES PATENT OFFICE.

GEORGE E. CLAYTON, OF LONG BEACH, CALIFORNIA.

WAVE AND CURRENT MOTOR.

Application filed March 18, 1926. Serial No. 95,583.

An object of my invention is to provide a wave or current motor, in which the power shaft is continuously rotated in one direction irrespective of the movement of the 5 paddle wheel.

Another object is to provide a plurality of motors all acting to continuously rotate a power shaft.

Further objects are to provide a motor 10 of the character stated which is simple in construction, and effective in operation.

Other objects advantages and features of invention may appear from the accompanying drawing and subjoined detailed description and the appended claims.

In the drawings illustrating my invention.

Fig. 1 is a side elevation of my motors in operative position.

Fig. 2 is a fragmentary plan view of the 20 same.

Fig. 3 is an end view of a motor with the hood removed.

Fig. 4 is a fragmentary sectional view of the power shaft.

25 Fig. 5 is an enlarged fragmentary transverse sectional view of the motor.

Fig. 6 is an enlarged sectional view taken on line 6—6 Fig. 5.

Referring more particularly to the drawing.

My motors *a* may or may not be placed in tandem as shown in Figs. 1 and 2. The motors each comprise pontoons 1, 2, which are preferably cylindrical bodies each of which are pointed at both ends as at 3. The pontoons float on the water and a paddle wheel 4 is rotatably mounted between them, with the axial line thereof about on a line with the top of said pontoons. A hood 5 rests on the top 35 of the pontoons 1, 2 and the upper half of the wheel 4 is enclosed thereby. The purpose of the hood is to prevent a wave from simultaneously striking both the upper and lower wheel blades, and thus not rotate the wheel.

40 The hood encloses the upper blades of the wheel 4, and the lower part of said wheel is all that is exposed to the force of the waves, and rotation of the wheel is thus insured. The pontoons 1, 2 are each slidably mounted

45 on a pair of vertical guide posts 6—7 respectively which posts are securely embedded in a suitable foundation 8. These posts extend through sleeve 6'—7' in the pontoons 1, 2 which serve as guides and still withhold 50 the water from the inside of said pontoons,

any other desirable guide means may also be employed.

The pontoons 1, 2 are each provided with a depending apron 9, 10 respectively, which extend longitudinally thereof and along the 60 inner surface so that the force of the wave is directed inwardly towards the wheel 4.

A shaft 11 extends across the pontoons and is journaled in a bearing 12 on the pontoon 1. A sleeve 13 surrounds the shaft 11 and the wheel 4 is secured thereto. A uni-directional clutch means 14 is provided on the wheel 4 to couple said wheel to the shaft 11. This clutch includes a housing 15 formed on the wheel 4 about the shaft 11, and a cover plate 16 closes the outer end thereof. A ratchet wheel 17 is secured to the shaft 11 and dogs 18 are pivotally mounted on the housing 15 and engage the ratchet wheel to 70 rotate the shaft in one direction only.

A housing 19 is mounted on the pontoon 2 and the shaft 11 and sleeve 13 extend into said housing. A vertical drive shaft 20 is journaled in the housing 19 and rises therefrom. This drive shaft is rotated constantly in one direction by the following means.

A bevel gear 21 is secured to the lower end of the drive shaft 20, and bevel gears 22, 23 mesh therewith. The gear 22 is secured to a drum 24, and the drum and gear are journaled on the shaft 11. A ratchet wheel 25 is secured to the sleeve 13 and dogs 26 are pivoted to the drum 24 and engage said wheel in only one rotational direction.

The shaft 20 is constantly rotated in one direction as follows: clockwise rotation of the wheel 4 (looking from the left) causes the dogs 18 to slip over the wheel 17, the sleeve 13 rotating drum 24 and gear 22, thus rotating gear 21 and shaft 20. Counter clockwise rotation of the wheel 4 causes the dogs 18 to engage wheel 17 and rotate the shaft 11. The dogs 26 slip over the ratchet wheel 25 so that the drum 24 is not driven. The dogs 29 engage the ratchet wheel 28 to drive the drum 27 and gear 23 which rotates the shaft 20 in the same direction as when rotated by the gear 22.

A slip joint 30 is provided in the shaft 20 to compensate for the rise and fall of the pontoons 1, 2 on the posts 6, 7.

A power shaft 31 is journaled on a platform 32 on top of the posts 6, 7, and is driven from the shaft 20 by the level gears

33, 34. A drum 35 to which the gear is secured is freely rotatable on the shaft 31 and dogs 36 on said drum are adapted to engage the ratchet wheel 37 secured to said shaft to drive the same. A second drum 38 is journaled on the end of the shaft 31 opposite the drum 35, and dogs 39 pivoted to the drum are adapted to engage a ratchet wheel 40 secured to said shaft to drive the same. A bevel gear 41 secured to the drum 38 meshes with a gear 42 on a shaft 43 which shaft extends to, and is driven by, the second motor is tandem with the first, in the same manner as previously described.

15 Thus when the first motor is operating the ratchet wheel 37 is engaged by the dogs 36 to rotate the shaft 31, while when the second motor operates the ratchet wheel 40 is engaged by the dogs 39 to rotate said shaft and the dogs 36 slip over the ratchet 37 permitting the shaft 20 to remain stationary.

If desired a jack shaft 45 may be driven by gearing 46 from the power shaft 31, and any desired mechanism is then driven by the 25 jack shaft.

The operation of my invention is evident from the foregoing description. It will be seen that the power shaft 31 is constantly driven irrespective of the direction of rotation of the paddle wheel 4. Each of the unidirectional clutches comprising drums, dogs and ratchet wheels are similar to that shown in Fig. 6.

Having described my invention I claim.

35 1. A wave and current motor comprising a pair of pontoons a shaft journaled on said pontoons, a sleeve surrounding said shaft, a paddle wheel secured to said sleeve, unidirectional clutch means coupling said shaft and said wheel, a drive shaft, unidirectional clutch means coupling said sleeve and said drive shaft, unidirectional clutch means coupling said first named shaft and the drive shaft whereby rotation of said wheel in 40 either direction will rotate said drive shaft in one direction.

2. A wave and current motor comprising a pair of pontoons, a paddle wheel rotatably mounted between said pontoons, a drive shaft, means coupling said drive shaft and paddle wheel whereby either directional rotation of said wheel will rotate said drive shaft in one direction, a power shaft, gear means connecting said power shaft and said drive shaft, a second pair of pontoons, having a paddle wheel journaled thereon and a drive shaft substantially as described, and drive means connecting said power shaft and said second drive shaft, said drive 55 means comprising a shaft adapted to be rotated by said second drive shaft, gear means connecting said shaft and power shaft, and unidirectional clutch means coupling said shaft and the power shaft.

60 65 3. A wave and current motor comprising a

pair of pontoons a shaft journaled on said pontoons, a sleeve surrounding said shaft, a paddle wheel secured to said sleeve, unidirectional clutch means coupling said shaft and said wheel, a drive shaft, unidirectional clutch means coupling said sleeve and said drive shaft, unidirectional clutch means coupling said first named shaft and the drive shaft whereby rotation of said wheel in either direction will rotate said drive shaft in one direction and a hood on said pontoon enclosing the upper part of said paddle wheel.

4. A wave and current motor comprising a pair of pontoons, a shaft journaled on said pontoons, a sleeve surrounding said shaft, a paddle wheel secured to said sleeve, a ratchet wheel secured to said shaft, dogs pivoted to the paddle wheel and adapted to engage said ratchet wheel in one direction only, a drive shaft, a gear on said shaft, a pair of gears meshing with said gear on the shaft, and unidirectional clutch means securing one of said pair of gears to the sleeve and the second of said pair of gears to the shaft.

5. A wave and current motor comprising a pair of pontoons, a shaft journaled on said pontoons, a sleeve surrounding said shaft, a paddle wheel secured to said sleeve, a ratchet wheel secured to said shaft, dogs pivoted to the paddle wheel and adapted to engage said ratchet wheel in one direction only, a drive shaft, a gear on said shaft, a pair of gears meshing with said gear on the shaft, and unidirectional clutch means securing one of said pair of gears to the sleeve and the second of said pair of gears to the shaft a power shaft, and unidirectional clutch means coupling said drive shaft and power shaft, a power shaft, and unidirectional clutch means coupling said drive shaft and power shaft.

6. A wave and current motor comprising a pair of pontoons, a shaft journaled on said pontoons, a sleeve surrounding said shaft, a paddle wheel secured to said sleeve, a ratchet wheel secured to said shaft, dogs pivoted to the paddle wheel and adapted to engage said ratchet wheel in one direction only, a drive shaft, a gear on said drive shaft, a pair of gears meshing with said gear on the shaft, and unidirectional clutch means securing one of said pair of gears to the sleeve and the second of said pair of gears to the first named shaft, a power shaft, and unidirectional clutch means coupling said drive shaft and power shaft, a second pair of pontoons having a paddle wheel and a drive shaft adapted to be driven by said paddle wheel, a shaft connecting said second drive shaft and said power shaft, and unidirectional clutch means coupling said power shaft and said last named shaft.

In testimony whereof I affix my signature.

GEORGE E. CLAYTON.
